UNITED STATES PATENT OFFICE.

CHARLES A. MOORE, OF ST. PAUL, MINNESOTA.

VENTILATING, HEATING, AND HUMIDIFYING APPARATUS.

Application filed August 15, 1924. Serial No. 732,346.

My invention relates to improvements in apparatus for conditioning the atmosphere in a room by heating, ventilating and humidifying the same.

5 One object is to provide an apparatus of the present nature, embodying a novel structure that is simple, durable, and relatively inexpensive and capable of efficiently carrying out the purposes of the invention.

10 More specifically it is my object to provide a novel and efficient arrangement of parts in an apparatus of the present kind, wherein a heating element may be employed, not only as an air heater and circulation 15 stimulator, but as an effective humidifying medium as well.

With the foregoing and other objects in view, which will appear in the following description, the invention resides in the novel 20 combination and arrangement of parts and in the details of construction hereinafter described and claimed.

In the drawings, Fig. 1 is a vertical, central sectional view of an apparatus embodying my invention; Fig. 2 is an end elevation thereof and Fig. 3 is a horizontal sectional view taken on the line 3—3 of Fig. 1.

Reference being had to the drawings, wherein similar reference characters have 30 been used throughout the several views to designate similar parts, it will be observed that my improvement includes two upright ducts A, B arranged side by side in a chamber C. The top of the duct A falls short 35 of the ceiling 10 of the chamber C and the bottom of said duct falls short of the floor 11 of said chamber. Said duct A has a damper 12 near the lower end thereof and is fitted with branch-ducts a', a'', just above 40 said damper 12. The branch-duct a' has communication with the outer air through the wall 13 of the chamber C and is fitted with a damper 14. The branch-duct a'' opens into the chamber C and is also fitted with 45 a damper, the same being designated by the numeral 15. The duct B falls short of the floor 11 at its lower end, the upper end of said duct being open to the outer air through the ceiling 10 of the chamber C.

50 Near the lower end of the duct B a damper 16 is fitted therein. Said duct B is supplied with a branch-duct b near the ceiling 10 of the chamber. This branch-duct b and the duct B are respectively fitted with 55 dampers 17, 18, the latter being located above said branch duct. A drum-like base

D with openings 19 at its lower margin, receives the lower ends of said ducts A, B and supports a tank E through which said ducts pass. A valved filler pipe 20 supplies water 60 to this tank and a drain pipe 21 opening near the top of the tank E provides for the maintenance of the water level as shown in Fig. 1. Said drain pipe 21 empties into the basin 22 in the floor 11 of the chamber, 65 which, in turn, empties into any convenient sewer or other drain as at 23.

Encircling that portion of the duct A surrounded by water in the tank E is a sleeve F. The body 24 of said sleeve F has an inner lining 25 spaced apart therefrom, the space between said body and lining being vacuous or packed, fluid tight, with a suitable temperature insulating medium such as cork 26 or the like. The inner surface of 70 the lining 25 lies closely adjacent to that portion of the duct A encircled by said lining. Spacer legs 27 depending from the lower edge of the sleeve F support said sleeve upon the bottom of the tank E with said 75 edge slightly above said bottom, the legs 27 serving also to hold the sleeve in concentric relation with respect to said duct A. The upper margin of the sleeve body 24, which extends above the lining 25 is formed with 80 a series of aligned, horizontal openings 28 in the plane of the water level in the tank E. Thus it will be understood that the restricted space between the sleeve lining 25 and the duct A is open at the bottom of 85 the sleeve F into the bottom of the tank E and at the top of said sleeve into said tank 90 at the water level therein.

Hung within the duct A are a number of 95 electrical heating elements G of conventional type, the same being joined at their ends by spacer mountings 29 in the form of rings. Hangers 30 reaching upward from the upper ring 29 are hooked at their upper ends as at 30a and caught over the upper edge of the duct A (Fig. 1). Said heating elements G heat the air within the duct A and, being arranged near the wall of said duct, intensely heat, through said wall, the limited quantity of water in the restricted 100 space between the sleeve F and conduit A. Being thus heated ample evaporation of the water is accomplished to meet the requirements for humidification within the chamber. Extending above the upper end of the 105 duct A, the upper margin of the sleeve body 24 directs the rising vapor into the current 110

of air circulated upwardly in the duct A through the effect of the heating elements G therein. The water in the restricted space between the sleeve F and duct A being in communication at the top and bottom of said sleeve with the larger quantity of water in the tank, a circulation of the water is set up through said restricted space. Due to this circulation the duct B is substantially 10 heated by the water, the effect thereof being to raise the temperature of the air within said duct and thereby stimulate its upward movement therethrough.

In use, as for example, in a ripening room 15 with the dampers 14, 16 and 18 opened, the air in the duct A, heated and urged upwardly by the elements G, has ingress from without the chamber into the upper portion thereof, said air being supplied with vapor 20 from the sleeve F. Heated by the surrounding water in the tank E, the duct B heats the air therein. Said air thus heated in duct B rises in said duct whereby is caused the egress of air from the lower portion of the 25 chamber C to the outside. Thus, it will be seen that the apparatus operates effectively to ventilate, heat and humidify the atmosphere within the chamber. Relative adjustment of the various dampers additionally results in a variously mixed ventilation and 30 internal circulation as will be readily understood. For example, in addition to opening the dampers 14, 16 and 18, the user may open damper 15. In this event and according to 35 the relative adjustments of said dampers, more or less of the air is recirculated in the room, some of the air at the lower portion of the room being drawn into branch duct α^2 and expelled into the upper portion of 40 the room from duct A, instead of being limited to entry into duct B, as would be the case were damper 15 to be closed. This practice of recirculating air is desirable when it is necessary to conserve heat. In 45 fact, ventilation may be avoided entirely and the device employed solely for heated, internal, circulation. This effect is obtained by closing dampers 14 and 18, leaving damper 15 open. And to augment this effect, dampers 16 and 17 may be opened, in 50 which event there is an upward movement of air in duct B from the lower portion of the room to the upper portion thereof. Also it will be understood that the skimming of 55 the upper stratum of air from the chamber C may be accomplished by the opening of the dampers 17 and 18.

Changes in the specific form of my invention, as herein disclosed, may be made 60 within the scope of what is claimed without departing from the spirit of my invention.

Having described my invention, what I claim as new and desire to protect by Letters Patent is:

65 1. The combination with a chamber, of

ingress and egress ducts leading upwardly therein, the former feeding air from without into the upper portion of the chamber and the latter exhausting air from the lower portion of the chamber to the outside, a tank through which adjacent portions of said ducts pass, a pipe for supplying fluid to said tank, an insulated sleeve closely encircling the ingress duct, the space between said duct and sleeve being restricted and opening at the bottom thereof into the lower portion of the tank, and at the top thereof into the upper portion of the tank beneath the fluid level therein, and a heating element within that portion of the ingress duct encircled by said sleeve, said element being adapted to heat the air in said duct and also heat the fluid in said restricted space.

2. The combination with a chamber, of air circulating ducts therein, a tank for fluid through which adjacent upright portions of said ducts pass, an insulated sleeve encircling one of said ducts, the space between said duct and sleeve opening at the top and bottom of the sleeve into the tank and a heating element associated with the sleeve encircled duct, said element being arranged within the confines of said sleeve and adapted to heat air in said duct and also fluid within said sleeve.

3. The combination with a chamber, of air circulating ducts therein, a tank through which said ducts pass, an insulated member forming with one of said ducts, a restricted space through which fluid in the tank may circulate, and means arranged to affect, primarily, the temperature of fluid in said space and the temperature of air within said duct and to affect, secondarily, the temperature of air within the other duct through the medium of said fluid.

4. The combination with a chamber, of air circulating ducts therein, a tank through which said ducts pass, a member adjacent one of said ducts and forming therewith a restricted space outside said duct through which fluid contained in said tank may circulate, and means arranged to affect the temperature of the air in said duct and also of the fluid about the same.

5. The combination with a chamber, of an upright air circulating duct therein, a sleeve closely encircling a portion of said duct and forming a restricted fluid receiving space about the same, means for supplying said space with fluid and a heating element associated with said duct within the confines of said sleeve, said element being adapted to heat the air in said duct and the fluid between said duct and sleeve.

6. In an apparatus of the class described, an air circulating duct therein, a member associated with said duct and forming therewith a restricted fluid receiving space at the outer side thereof, means for supplying said space with fluid and a heating element inside

of said duct and in near proximity to said member, said element being adapted to heat the air in the duct and the fluid between said duct and sleeve.

5 7. In an apparatus of the class described, an air circulating duct, a member associated with said duct and forming therewith a restricted space for water to be vaporized, and a heating element arranged with respect to 10 the duct and in near proximity to said member for heating air in the duct and also the water in said restricted space.

8. The combination with a chamber, of an upright air circulating duct therein, a tank

for fluid through which said duct passes, a 15 sleeve within the tank and encircling said duct, and means adapted to affect the temperature of and circulate the fluid in said tank, said means being arranged to affect in greatest degree the temperature of the fluid 20 in the space between said duct and sleeve, whereby the fluid is caused to move from said space into the tank outside of said sleeve and back again into said space.

In testimony whereof, I have signed my 25 name to this specification.

CHARLES A. MOORE.
